Primary Examiner — Robert M Spear*Assistant Examiner* — Darcey E Heflin(57) **CLAIM**

The ornamental design for packaging with surface ornamentation, as shown and described.

DESCRIPTION

FIG. 1 is a front elevational view of a packaging with surface ornamentation;

FIG. 2 is a front elevational view showing the packaging with surface ornamentation of FIG. 1 in an alternative unclaimed environment;

FIG. 3 is a front elevational view showing the packaging with surface ornamentation of FIG. 1 in a second alternative unclaimed environment; and,

FIG. 4 is a front elevational view showing the packaging with surface ornamentation of FIG. 1 in a third alternative unclaimed environment.

The broken lines showing the packaging are included for the purpose of illustrating environmental structure and form no part of the claimed design.
